(57) **CLAIM**

The design for a low profile self-sealing access port device, as shown.

DESCRIPTION

FIG. 1 is a top right perspective view of a low profile self-sealing access port showing my new design;

FIG. 2 is a top view showing my new design;

FIG. 3 is a right side view showing my new design. The left side view is a mirror image of the right side view showing my new design;

FIG. 4 is a front elevation view showing my new design. The rear elevation view is a mirror image of the front elevation view; and,

FIG. 5 is a bottom view showing my new design.
